UNITED STATES PATENT OFFICE.

LAZA TUNICH, OF GREENFIELD, MICHIGAN.

WORK-HOLDER.

1,147,830.

Specification of Letters Patent. Patented July 27, 1915.

Application filed March 27, 1915. Serial No. 17,331.

To all whom it may concern:

Be it known that I, LAZA TUNICH, a subject of the King of Hungary, residing at Greenfield, in the county of Wayne and 5 State of Michigan, have invented certain new and useful Improvements in Work-Holders, of which the following is a specification, reference being had therein to the accompanying drawings.

10 This invention relates to a work holder, and the primary object of my invention is to provide a novel rotary holder wherein positive and reliable means are employed, in a manner as hereinafter set forth, for 15 holding pieces of work while the same are subjected to the action of a grinding machine or otherwise treated or finished, the work holder eventually ejecting a piece of the work and obviating the necessity of 20 manual manipulation before a machine.

Another object of this invention is to provide a novel machine for continuously feeding pieces of work to a grinding machine, whereby the pieces of work can be 25 ground with uniformity and precluding any possibility of inaccuracy or injury as compared to hand manipulation of a piece of work against a grinding wheel, or surface.

A further object of this invention is to 30 provide a work holder that can be advantageously used as a part of a grinding machine for grinding or finishing valves adapted to form part of internal combustion engines; it having been heretofore the practice 35 for a workman to manually manipulate such valves against the surface of the grinding wheel to finish the same and such practice requires constant attention on the part of the workman and then with no assurance of 40 uniformity or perfection, besides at all times being liable to personal injury by the hands contacting with the grinding device.

The above and other objects are attained 45 by a work holder wherein the parts are constructed with a view of reducing the cost of manufacture and at the same time retain the features by which safety, durability, simplicity and ease of fabrication are secured, and with such ends in view, the invention resides in the novel construction, combination 50 and arrangement of parts to be hereinafter specifically described and then claimed.

Reference will now be had to the drawings, wherein—

Figure 1 is a side elevation of a work holder; Fig. 2 is a plan of the same; Fig. 3 is a front elevation of the work holder partly broken away; Fig. 4 is a rear elevation of the same partly broken away and partly in section, and Fig. 5 is an enlarged detail sectional view taken on the line V—V of Fig. 3; Fig. 6, is an enlarged detail sectional view taken on the line VI—VI of Fig. 3, and Fig. 7 is an enlarged detail sectional view taken on the line VII—VII of Fig. 3.

In describing my invention by aid of the views above referred to, I desire to point out that the same are merely illustrative of an example whereby my invention may be applied in practice, and I do not care to confine my invention to the precise construction and arrangement of parts shown. The following description is therefore to be broadly construed as including substitute 75 constructions and arrangement of parts which are the obvious equivalents of those to be hereinafter referred to.

In the drawings, the reference numeral 1 denotes a hollow base having the top thereof 80 provided with a longitudinal dove-tailed groove or guideway 2 for the depending longitudinal dove-tailed tongue 3 of a carriage 4 sliding upon the top of the base. The tongue 3 has a depending nut 5 in threaded 85 engagement with a feed screw 6 journaled in the upper part of the base 1. The feed screw 6 has a beveled gear wheel 7 meshing with a small beveled gear wheel 8 on the inner end of a shaft 9, journaled in the side 90 wall of the base. The outer end of the shaft 9 has a suitable handle or crank 10 and the elements 5 to 10 inclusive constitute adjustable means for moving the carriage 4 and correctly positioning the same relative 95 to a grinding machine. To hold the carriage 4 in adjusted position, said carriage is provided with a locking device comprising a screw 11, a clamping block 12 and a handle or crank 13, these elements being as best 100 shown in Fig. 4.

The carriage 4 is provided with bearings 14 for a longitudinal drive shaft 15 provided with a pulley 16, between the bearings 14 whereby the shaft 15 can be driven from 105 a suitable source of power, as a motor. The shaft 15 protrudes from one of the bearings 14 and is provided with a circular head 17,

said head having the outer side thereof provided with an annular integral flange 18 cooperating with the head 17 in forming a peripheral channel 19. The flange 18 has a plurality of equally spaced circumferentially arranged openings 20 alining with openings 21 in the head 17 and yieldably mounted in said openings are work holders 22. The work holders 22 have longitudinal bores 23 and heads 24, said bores accommodating the stems 25 of pieces of work 26, which have been shown as in the form of valves. The work holders are exteriorly screwthreaded for a portion of their length 15 to receive nuts 27 and encircling said holders, are coiled compression springs 28. These springs yieldably hold the work holders in the openings 20 and 21 and maintain said work holders normally in an extended 20 position.

The bearing 14, contiguous to the head 17, has a bracket 29 supporting a segment hood 30 which has the outer wall 31 thereof in front of a portion of the head 17, as best 25 shown in Figs. 3 and 7. An end of the wall 31 is flared, as at 32, whereby the valves 26 can be easily carried into engagement with the inner side of the wall 31, said wall serving functionally as a cam which forces the 30 work holders 22 inwardly, placing the springs 28 under additional tension. These springs however maintain the valves 26 against the wall 31 until the valves are carried into engagement with the face of a 35 grinding wheel or the grinding element of a suitable machine, and to indicate the position of such machine, the dot and dash line designated 33 in Fig. 3, indicates a wheel of sufficient diameter to permit of a plurality 40 of pieces of work being simultaneously ground.

By adjusting the nuts 27 the pressure of the pieces of work against the wall 31 and the grinding wheel can be regulated and to 45 facilitate adjusting the nuts under the hood 30, the top thereof is provided with a hinged door 34 normally closing an opening in the top of said hood.

The forward end of the carriage 4 is provided with a bracket 35 having a wall 36 in proximity to the grinding wheel and it is into engagement with this wall that pieces 50 of work are carried after being ground, the wall 36 preventing pieces of work from tilting or shifting until completely out of engagement with the grinding wheel. After 55 the pieces of work have wiped the wall 36, the pieces of work are ejected from the work holders by reason of the springs 28 imparting sufficient impetus to the work holders to 60 eject the pieces of work.

To prevent a rearward or counterclockwise movement of the head 17, the rear side of the head is provided with ratchet teeth 65 35^a and engaging said teeth is a spring

pressed pawl 36^a, carried by an extension 37 of the bearing 14 adjacent the head 17.

In operation, it is only necessary for an attendant of the machine to place the valves or pieces of work in the work holders as 70 the head 17 is slowly revolved, and with the attendant of the machine located upon that side thereof opposite the grinding machine there is no danger of the hand contacting with the grinding machine or the attendant 75 injured. The pieces of work are automatically ground and ejected from the work holders and in consequence of a machine of this type a large amount of work can be 80 expeditiously produced.

What I claim is:—

1. A machine of the type described, comprising a rotary head, a plurality of yieldable work holders carried thereby, means in front of said head adapted to maintain the 85 work holders in a retracted position preparatory to certain operations, and means in front of said head and opposite the first mentioned means adapted to retain said work holders in a retracted position until 90 such operations are completely finished.

2. In a work holder, the combination with a grinding wheel, of a carriage adjustable relative to said wheel, a rotary head supported by said carriage in front of a portion 95 of said wheel, a plurality of yieldable work holders carried by said head, means carried by said carriage in a plane with said grinding wheel and adapted to retain pieces of work in said holders and said holders in a 100 retracted position preparatory to engaging said grinding wheel, and means carried by said carriage in a plane with said grinding wheel adapted to hold said work holders in a retracted position preparatory to ejecting 105 work held thereby.

3. In a work holder, the combination with a grinding wheel, of a carriage adjustable relative thereto, a rotary head carried by said carriage in front of a portion of said 110 grinding wheel, a plurality of work holders on said head, means on said carriage in front of a portion of said rotary head and in the plane of said grinding wheel adapted to be engaged by pieces of work in said work 115 holders to retract said work holders preparatory to placing work in engagement with said grinding wheel, and means on said carriage in front of another portion of said rotary head and in the plane of said grinding wheel adapted to retain said work holders in a retracted position until the grinding 120 operation has been completely finished.

4. In a work holder, the combination with a grinding machine, of a carriage adjustable 125 relative thereto, a rotary head supported by said carriage, a plurality of yieldable work holders supported by said head, means adjacent said head adapted to retract said work holders preparatory to grinding operations 130

of said machine, and means on said carriage engaging said head adapted to prevent a counter clockwise movement thereof.

5. The combination with a grinding wheel, of a head movable relative thereto, a plurality of work holders yieldably supported by said head, and means in front of said head and in the plane of said grinding wheel adapted to retract said work holders pre-

paratory to placing pieces of work carried thereby in engagement with said grinding wheel.

In testimony whereof I affix my signature in presence of two witnesses.

LAZA TUNICH.
